US0D1112063S

(12) **United States Design Patent** (10) **Patent No.:** **US D1,112,063 S**
(45) **Date of Patent:** **** Feb. 10, 2026**

(54) **CHARGING DEVICE**

(71) Applicant: **Huzhou Luxshare Precision Industry Co., Ltd.**, Huzhou (CN)

(72) Inventor: **Tao Liu**, Huzhou (CN)

(73) Assignee: **HUZHOU LUXSHARE PRECISION INDUSTRY CO., LTD.**, Huzhou (CN)

(**) Term: **15 Years**

(21) Appl. No.: **29/962,865**

(22) Filed: **Sep. 13, 2024**

(30) **Foreign Application Priority Data**

Jul. 5, 2024 (CN) 202430419159.1

(51) **LOC (15) Cl.** **13-02**

(52) **U.S. Cl.**

USPC **D13/108**

(58) **Field of Classification Search**

USPC D13/103, 107, 108, 118, 119; D14/251, D14/252, 253, 447

CPC H02J 7/0044; H02J 7/0045; H02J 7/1423; H02J 9/002

See application file for complete search history.

(57) **CLAIM**

The ornamental design for a charging device, as shown and described.

DESCRIPTION

FIG. 1 is a perspective view of a charging device in accordance with my design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines in the drawings illustrate portions of the charging device that form no part of the claimed design.

1 Claim, 7 Drawing Sheets
